UNITED STATES PATENT OFFICE.

WILLARD C. LIPE, OF SYRACUSE, NEW YORK.

BROOM-SEWING MACHINE.

1,123,903.

Specification of Letters Patent.

Patented Jan. 5, 1915.

Application filed October 4, 1904. Serial No. 227,141.

To all whom it may concern:

Be it known that I, WILLARD C. LIPE, a citizen of the United States, and a resident of Syracuse, in the county of Onondaga and State of New York, have invented a certain new and useful Broom-Sewing Machine, of which the following is a specification.

This invention has for its object the production of a broom-sewing machine, which is especially simple in construction and particularly durable and effective in use; and to this end, it consists in the novel combinations and devices hereinafter set forth and pointed out in the claims.

In describing the invention, reference is had to the accompanying drawings in which like characters designate corresponding parts in all the views.

Figure 1 is a top plan, partly broken away, of one construction of my machine. Fig. 2 is a side elevation, partly broken away and in section, of the broom-sewing machine, shown in Fig. 1, the sewing mechanism, with the exception of the banding needle and the band-lifter, being removed. Fig. 3 is a top plan of the greater portion of the parts illustrated in Fig. 2. Fig. 4 is a sectional view, on line A—A, Fig. 3, of the upper end of the vise. Fig. 5 is a front elevation of the lower end of said vise. Figs. 6 and 7 are, respectively, top plan and inner face view of the broom-support, and contiguous parts of the vise. Fig. 8 is a detail view of the pawls for controlling the downward movement of the broom-support, and a part of the jaw supporting said pawls. Fig. 9 is a detail view of a portion of the means for raising the broom-support. Fig. 10 is a detail view, partly broken away and in section, of the engaging means secured to the movable jaw, and coacting with the cams for moving said jaw. Fig. 11 is an enlarged end view of said engaging means. Figs. 12 and 13 are, respectively, top plan and front elevation of the banding needle, the gage therefor, the needle-support and parts of the vise, a portion of a broom being shown in Fig. 12. Fig. 14 is a side elevation, partly in section, of the means illustrated in Figs. 12 and 13. Fig. 15 is a sectional view, on line B—B, Fig. 12. Fig. 16 is a sectional view, partly in elevation, of the reversely-movable driven member connected to the vise, and the means for supporting said driven member, for driving the same in reverse directions as the vise moves

to and fro, and for holding the driven member in its adjusted position, as the vise moves step by step. Fig. 17 is a top plan of the greater portion of the parts seen in Fig. 16. Fig. 18 is a sectional view of the detached reversely-movable driving member shown in Figs. 16 and 17. Figs. 19 and 20 are, respectively, top plan and face view of one of the ratchet-pawls coacting with said driving member. Figs. 21 and 22 are, respectively, top plan and edge view of a portion of the plate for partly inclosing the ratchet-teeth of the driving member, seen in Fig. 18. Fig. 23 is a sectional view, partly in elevation, of the driving member provided with an adjustable part for controlling the length of the advance steps of the vise, and contiguous portions of the machine, the adjustable part being shown in its inner position. Fig. 24 is a sectional view similar to Fig. 23, the adjustable part being illustrated in its extreme outward position. Fig. 25 is a top plan of means seen in Fig. 23. Fig. 26 is a sectional view on line C—C, Fig. 23. Fig. 27 is a rear elevation of the greater portion of the means for varying the position of the adjustable part of the driving member which controls the length of the advance steps of the vise, and contiguous portions of the machine. Fig. 28 is a side elevation, partly in section, of the means shown in Fig. 27. Fig. 29 is a top plan of parts, seen in Figs. 27 and 28. Fig. 30 is an isometric view of a member of the adjustable connection illustrated in Figs. 27, 28, and 29. Fig. 31 is a side elevation, partly in section, of the reciprocating part seen in Figs. 27 and 28. Fig. 32 is a vertical sectional view of a vise provided with a modified construction of broom-support. Fig. 33 is an inner face view of one of the jaws of the vise and the broom-support illustrated in Fig. 32. Fig. 34 is a top plan of the broom-support seen in Figs. 32 and 33. Fig. 35 is a sectional view on line D—D, Fig. 33. Fig. 36 is a top plan of a further modified broom-support. Fig. 37 is a sectional view on line E—E, Fig. 36. Figs. 38 and 39, are, respectively, rear and side elevations of a driving member provided with a modified construction of adjustable part for controlling the movement of the vise, and contiguous portions of the machine. Fig. 40 is a sectional view of means shown in Fig. 38, the adjustable part of the driving member being illustrated in its inner position.

tion. Fig. 41 is a sectional view similar to Fig. 40, said adjustable part being in its extreme outward position. Fig. 42 is a face view of the detached driving member illustrated in Figs. 38 to 41, inclusive, the means for moving the adjustable part thereof, being shown in section. Fig. 43 is a top plan, partly broken away, of said driving member. Figs. 44 and 45 are, respectively, top plan and rear elevation of a modified construction of means for varying the position of the adjustable part of the driving member which controls the length of the advance movements of the vise.

15 The illustrated embodiment of this invention, comprises a main frame 1, a vise 2, and sewing and feeding mechanisms. As is apparent, the frame 1 is of any desirable form, size and construction. The vise 2 usually comprises opposing upright jaws 3, 4, and a broom-support. Said jaw 3 is shown, Fig. 2, as secured at its intermediate portion to the frame 1 by a horizontal pivot 5 upon which the jaw 3 moves to and fro, 25 or in opposite directions from front to rear of the machine and toward and from the needle-path. A suitable spring 6, Fig. 2, is connected to the frame 1 and the lower end of the jaw 3 and subjects the vise to an increasing resistance when moving in either 30 direction beyond its intermediate position, thus storing energy in the spring 6 which tends to move the vise in opposite directions to said intermediate position. This spring 35 and the means for connecting the same to the frame and the vise form no part of my present invention, and as they are fully shown and described in my prior Patent 718,263, dated Jan. 13, 1903, it is thought 40 unnecessary to further describe the same herein.

As best seen in Figs. 4 and 5, the jaw 4 is movable laterally toward and from the jaw 3 and is provided at its lower end with 45 lateral extensions 7, Figs. 2 and 5, secured by a pivot 8 to the jaw 3. The means for moving the jaw 4 laterally, as illustrated, consists of two cams 9 and engaging means 10, the cams 9 being fixed to the ends of a 50 common shaft 11 journaled in the fixed jaw 3 and forming part of a manually-operated actuating member 12, and the engaging means 10 consisting of pivoted slides, Figs. 4, 10 and 11, which are supported on the 55 ends of a shaft carried by the movable jaw 4 and engage camways in the opposing sides of the cams 9. The movement of the jaw 4 laterally from the jaw 3 may be limited by any desirable means, not illustrated, nor 60 normally fixed to the frame 1.

The broom-support, as preferably constructed, consists of opposing engaging parts 13 for clamping the broom independently of the jaws 3, 4, attaching parts 14 supporting the parts 13, and means for mov-

ing the attaching parts and the engaging parts carried thereby toward and from each other. The engaging parts 13 are movable independently of the jaws 3, 4, toward and from a line substantially coincident with the 70 axis of the broom when clamped by said jaws, and in a direction at substantially a right-angle to the line of movement of the jaw 4 and the plane in which the jaws 3, 4, compress the broom. These parts 13 are 75 pivoted intermediate of their ends at 15 to the attaching parts 14, are movable on their pivotal axes independently of said parts 14, and are usually formed with curved upper faces and with upper and lower engaging 80 surfaces 16, 17, arranged, respectively, above and below the pivots 15, the lower ends of the engaging parts 13, provided with the surfaces 17, being comparatively thin and formed of spring material, and being 85 movable or yielding independently of the upper ends of said parts 13, when engaged with the broom. In the preferable construction of my broom-support, the attaching parts 14 are mounted upon 90 the upper ends of levers 18 pivoted intermediate of their ends to a supporting frame 19 carried by the fixed jaw 3. These parts 14 are adjustable lengthwise of the upper 95 ends of the levers 18 forming guides for said parts, and are held in their adjusted position by suitable clamping means, as screws 20. It is thus apparent that the attaching parts 14 are movable in a plurality of directions relatively to the jaws 3, 4.

100 The means for moving the attaching parts and the engaging parts carried thereby toward and from each other, consists of the levers 18, and means for rocking said levers on their pivots, relatively to the jaws 3, 4, 105 and the frame 19, said means being here shown as a spring 21, reciprocating members 22 and cams 23. The spring 21 is interposed between the opposing faces of the lower ends of the levers 18 and forms means 110 for yieldingly forcing the parts 13 into engagement with the broom independently of the vise-jaws 3, 4. This spring 21 may be supported on a rod 24 connecting the lower ends of the levers 18, and in such event is 115 carried by said levers 18. The reciprocating members 22 are guided in the jaw 3 in a plane substantially parallel to the shaft 11, and the opposing or inner ends thereof are engaged with the outer faces of the lower 120 ends of the levers 18 for moving the engaging parts 13 from the broom independently of the vise-jaws 3, 4. The outer ends of the reciprocating members 22 are engaged by the cams 23 which generally consist of cam-surfaces provided upon the opposing surfaces of the cams 9 previously described. 125 As will be apparent to those skilled in the art, the cams 23 are so arranged relatively to the cam-ways for receiving the engaging 130

means 10, that when the cams 9 coact with said means 10 to open the opposing jaws of the vise, the cams 23 move the reciprocating members 22 endwise toward each other, and 5 through the medium of the levers 18 force the engaging parts 13 from the broom. As the cams 9 commence their reverse movement for closing the opposing jaws 3, 4, of the vise, or in other words, for moving the 10 jaw 4 laterally toward the jaw 3, the cams 23 permit the reciprocating members 22 to move outwardly under the influence of the spring 21, and, consequently, said spring 15 yieldingly engages the parts 13 with the broom, it being understood, however, that the broom is operatively engaged by the parts 13 before the jaw 4 commences to compress the broom against the jaw 3. Since the broom-support is solely supported upon 20 the fixed jaw 3, the jaw 4 moves independently of said broom-support and preferably in a direction at substantially right-angles to the line of movement of the engaging parts 13 toward and from each other.

25 A broom-support having engaging parts constructed and actuated, as described, is particularly applicable for supporting brooms having short handles of ununiform shapes and sizes, as brush-brooms, since said broom-support firmly engages such handles 30 and holds the same in the desired position.

In the preferable construction of this invention, the broom-support is movable, as a whole, relatively to the vise-jaws 3, 4, 35 downwardly and upwardly lengthwise of a line substantially coincident with the axis of the broom, in order that said support may hold the broom in proper position to receive successive rows of stitches. As here 40 illustrated, the broom-support moves downwardly by gravity, and is manually controlled in such movement by a rack 25 secured to said broom-support by a clamping member 26 and an eccentric sleeve 27, a pair 45 of pawls 28, 29, engaging the rack 25, and cams 30, 31, provided on the shaft 11 and coacting with the pawls 28, 29, to permit the broom-support to feed downwardly step by step, as the shaft 11 is rocked to 50 and fro by the actuating member 12. When the broom-support has reached the limit of its downward movement, it may be returned by rocking the actuating member 12 on its axis beyond its position assumed when said 55 member has forced the jaw 4 to the limit of its outward movement, whereupon a crank-arm 32 provided on the shaft 11 engages a loose sleeve 33 carried by said shaft 11 and connected by a link 34 to the rack 25, and 60 forces said rack upwardly to its elevated position for holding the broom in position to receive the first row of stitches. The means for controlling and effecting the movement of the broom-support, as a whole, 65 vertically relatively to the vise-jaws is fully

shown and described in my aforesaid Patent 718,263, and further description thereof herein is deemed unnecessary.

Although the described broom-support is particularly simple in construction and effective in operation, other devices may be substituted therefor, as those seen in Figs. 32 to 37 inclusive, the broom-support illustrated in Figs. 32 to 35 comprising reciprocating attaching parts 35 and engaging 70 parts 36 adjustably secured thereto and provided with yielding lower ends 37, and the support shown in Figs. 36 and 37 being provided with a tubular frame 38 and a plurality of inwardly-projecting radial 75 spring arms 39 having outwardly-yielding 80 free ends forming broom-engaging parts.

As illustrated, I have provided a banding needle 40 and sewing mechanism, the latter comprising stitch-forming needles 41, 42, loopers 43, 44, and a band-lifter 45. Said banding needle 40, Figs. 12, 13 and 14, is preferably fixed to one end of a part or lever 46 which is provided at its other end with a hand-piece 47, and is pivoted intermediate of its ends at 48 to a support 49 movable with the vise and reciprocally-movable rectilinearly relatively to said vise in a guide or socket 50 in the movable jaw 4. A gage 51 is fixed to the part or lever 46 90 in proximity to the needle 40, and is thus movable with the vise and the needle. The free end of the gage projects laterally beyond the point of the needle, and its other end is adjustable rectilinearly on the lever 100 46 in any suitable manner toward and from the needle 40, and is held in its adjusted position by a clamping screw 52. A spring 53 moves the part or arm 46 relatively to the broom-vise and the support 49, and a spring 105 54 movable independently of the spring 53 forces the support 49 and the parts carried thereby relatively to the vise to their initial positions.

In the use of my banding needle, the operator grasps the hand-piece 47 and moves the same in a line parallel to the path of movement of the support 49, thus forcing said support and the parts carried thereby rectilinearly relatively to the vise against 115 the action of the spring 54 until the projecting free end of the gage 51 is substantially coincident with the plane of the front edge of the broom clamped by the jaws 3, 4, being preferably engaged with said front 120 edge, whereupon the needle 40 is in operative position. The operator, while still grasping the hand-piece 47, swings the lever 46 on its pivot relatively to the vise and the support 49, thus moving the needle in 125 a direction at an angle to its reciprocal movement and forcing the free end thereof through the broom. A banding cord is then engaged with the needle 40 and is drawn thereby through the broom upon the re- 130

turn of the needle. After the engagement of the banding cord with the needle 40, the operator releases the hand-piece 47, whereupon before either of the needles 41, 42, 5 engage the broom, the springs 43, 54, automatically rock the lever 46 relatively to the support 49 and thus return the needle with the banding cord through the broom, disengage the needle 40 from the broom, and 10 move the support 49 to its initial position. It will be understood, however, that the operator, may, if he prefers, return the needle 40 and its support by hand.

The needles 41, 42, the loopers 43, 44, and 15 the means for supporting and actuating said parts constitute the stitch-forming mechanism of my machine, but said mechanism is substantially identical with that shown and described in my prior Patent, No. 718,263, 20 and hence description thereof herein is deemed unnecessary, particularly as it will be apparent to those skilled in the art that any suitable stitch-forming mechanism may be employed in this machine. The band-lifter 45 is also substantially the same as the 25 like part in said patent and forms no part of this invention and, consequently, description thereof is omitted.

The feeding mechanism preferably comprises a driven member 55, Figs. 2 and 16, a driving member 56 and a driving element 57, for moving the member 55 in reverse directions for effecting, respectively, forward and retrograde movements of the vise, and a 30 driving means 58, Figs. 2 and 26, having a part 59 adjustable for controlling the amount of movement of the vise. As illustrated, the driven member 55 consists of a screw revoluble about an upright axis and 35 constantly meshing with a rack 60 fixed to the vise and arranged substantially parallel to a line coincident with the axis of the broom when clamped by the vise. As will 40 be apparent to those skilled in the art, the member 55 is thus revoluble in reverse directions as the vise moves to and fro, and the peripheral threads or shoulders thereof tend to hold the vise in its adjusted position. The driven member 55 is shown as fixed 45 to a shaft 61 which is reversely - revoluble with said member 55, is journaled in any desirable bearings 62, and is provided with an antifriction thrust-bearing 63 of any suitable construction for resisting the tendency 50 of the member 55 and its shaft 61 to move endwise when feeding the vise step by step during the sewing of the broom.

As here illustrated, the driving member 56, Figs. 16, 17 and 18, consists of a pinion 60 which is concentric with the driven member 55, is supported by the shaft 61, is loose on said shaft, being journaled on an upwardly projecting hub 64 of the driven member 55, and is movable in reverse directions by a 65 reciprocating rack 65 constantly meshing

therewith. A suitable ratchet-device is interposed between the members 55, 56, for moving the driven member 55 with the member 56 in one direction, and permitting said member 56 to move backwardly relatively to the driven member. As shown, this ratchet-device comprises a ratchet-wheel 66 and pawls 67, the wheel 66 consisting of a projecting flange on the driving member 56 arranged in a socket 68 extending inwardly from the upper face of the driven member 55, and having peripheral ratchet-teeth, and the pawls 67 being journaled in the driven member 55 on axes substantially parallel with the axis of the shaft 80 61, and having their upper ends provided with lateral extensions 69 movable in the socket 68 and coacting with the teeth of the wheel 66, and having their lower ends extended beneath the contiguous portions of 85 the driven member 55 and provided with lateral extensions 70 arranged beneath the extensions 69 and substantially parallel thereto. One of the pawls 67 is normally operatively engaged with one of the teeth of 90 the ratchet-wheel 66 for rotating said wheel, and the faces of the other pawls, for coacting with the teeth of said wheel to rotate the same, are dissimilarly separated from the contiguous teeth of the ratchet-wheel, 95 as best seen in Fig. 17. The portion of the driving member 56 provided with the teeth meshing with the rack 65 projects above the socket 68 and a ring 71, Figs. 16, 21 and 22, which ring surrounds the driving member 100 56 and forms a cover for the portion of the socket 68 encircling said member 56, the inner portion of the ring being arranged in an annular groove 72 formed in the driving member 56 between the gear and ratchet-teeth thereof. Suitable springs 73, Fig. 16, encircle the lower projecting ends of the pawls 67 and hold said pawls in engagement with the ratchet-wheel 66.

In order to permit the driven member 55 to move backwardly relatively to the driving member 56, the pawls 67 are forced from operative engagement with the ratchet-wheel 66 by any desirable means, as a sleeve 74 loosely encircling the shaft 61 and movable lengthwise thereof, the upper end of said sleeve being provided with an inclined surface 75 which forces the extensions 70 of the pawls 67 outwardly as the sleeve is elevated and thus disengages the extensions 69 of said pawls from the teeth of the ratchet-wheel 66. The upper end of the sleeve 74 provided with the surface 75 is usually formed separable from the underlying portion of said sleeve and is mounted on an antifriction thrust-bearing 76 which reduces to a minimum the friction on the parts when the pawls 67 are held out of operative position. The means for engaging the sleeve 74 with the extensions 70 of the pawls 67 130

may consist of a lever 77 pivoted intermediate of its ends to the frame 1 and having one end provided with a treadle 78, and its other end provided with an upwardly-extending arm 79 pivotally connected to a collar 80 surrounding the sleeve 74 and having its opposite portion pivoted at 81 to a bracket 82 on the frame 1. Contiguous surfaces of the sleeve 74 and the collar 80 are connected by suitable pivotal connections, as trunnions 83, Fig. 16, projecting from opposite sides of the sleeve 74 and journaled in the collar 80. As the treadle 78 is depressed, the sleeve 74 is moved upwardly lengthwise of the shaft 61 and forces the pawls 67 out of engagement with the ratchet-wheel 66, thus preventing the transmission of motion from one of the members 55, 56, to the other by the ratchet-device and permitting the driven member to move backwardly relatively to the driving member, as when the vise is being returned. As best seen in Fig. 2, the rack 60 fixed to the vise is generally provided with a shoulder 84 which, as the vise reaches the limit of its advance movement, encounters a shoulder 85 on the arm 79 and moves the sleeve 74 upwardly, thus forcing the pawls 67 from operative position.

By the use of the described ratchet-device, and the means for forcing the pawls of said device from operative position, the driven member 55 is propelled in one direction with the driving member 56, and either of said members is permitted to rotate in the reverse direction relatively to the other. It is thus possible to constantly engage the driven member with the vise, and to dispense with means for disengaging these parts. Moreover, the ratchet-pawls, arranged as shown and described permit of minute adjustments of the feed of the vise.

The driving hand-actuated element 57 facilitates the return of the broom-vise to its initial position by moving the driven member 55 in the opposite direction to that in which said member 55 is driven by the member 68. This driving element 57 is fixed to the shaft 61 and constantly meshes with a reciprocating rack 86 guided in the frame 1 and connected to the lower end of a lever 87 pivoted intermediate of its ends at 88 to the vise above the pivot 5 for said vise, and having its upper end provided with a hand-piece 89. The lever 87 serves as a convenient means for forcing the vise in either direction, and by connecting said lever to the vise and to the driving element as shown and described, the movement of the vise is greatly facilitated.

The illustrated embodiment of this invention is provided with friction-means for holding the vise in its adjusted position when moving step by step, such means consisting of a lower friction-collar 90 fixed to

the shaft 61, and an upper friction-collar 91 loose on the shaft 61 and movable lengthwise thereof and usually provided on the lower face of the sleeve 74, which sleeve may, if desired, constitute said upper collar. The weight of the sleeve 74 may be utilized as the force for engaging the collars 90, 91, but I prefer to augment the action thereof by an additional weight 92, Fig. 2, connected to the lever 77. When the vise is feeding step by step, the friction-collars 90, 91, are in engagement and hold said vise in its adjusted position, and whenever the treadle 78 is depressed, or the shoulder 84 movable with the vise is engaged with the shoulder 85, the collar 74 in addition to forcing the pawls 67 from operative position, simultaneously relieves the vise from said friction-means. A comparatively light weight for engaging the collars 90, 91, is sufficient, since by utilizing a screw to move the vise step by step, it is possible to hold the same in its adjusted position by means which subjects said vise to but little additional friction and does not materially retard the forward feeding thereof.

In the preferable construction of my invention, the driving means 58 is mounted on the main shaft 93, Fig. 2, and the adjustable part 59 of said means, Fig. 26, for regulating the length of the advance steps of the vise during the sewing of the broom, is pivoted intermediate of its ends to the main body of the means 58 by a pivot 94 arranged parallel to the axis of the means 58. Said main body of the driving means 58 is provided with a peripheral cutout 95, Figs. 25 and 26, and with peripheral engaging faces 96, 97, arranged one in advance of the other and in advance of said cutout, the face 97 being substantially equidistant throughout its length from the axis of the means 58, and the face 96 being arranged in advance of the face 97 and extended inwardly toward the axis of the means 58 from its rear end, and being essentially cam-shaped. The advance end of the adjustable part 59 is arranged in the cutout 95 at one side of the rear end of the engaging face 97, and the rear end of said part 59 projects into a peripheral groove 98 in the face 96 and the advance end of the face 97, and is adjustable toward and from the axis of the means 58. As clearly seen in Fig. 26, the outer edge of the portion of the adjustable part 59 in alignment with a radial line passing through the axes of the shaft 93 and the pivot 94 of the adjustable part 59 is substantially concentric with said pivot 94, and is also substantially tangent with the rear end of the face 97. The outer edge of the remaining portion of the part 59 is of substantially the same radius as that of the face 97, and when said part is in

operative position, Fig. 26, is arranged substantially cam-shaped relatively to the main body of the driving means and within a circular line 99, coincident with the face 97, but when the part 59 is moved outwardly to its extreme limit into inoperative position, Fig. 24, said outer edge is substantially concentric with the axis of the shaft 93 and coincident with such circular line 99. A suitable spring 100 engages the end of the adjustable part 59 at one side of the rear end of the face 97 for returning said part 59 to its inner position, and a reciprocating actuating member 101 engages the inner edge of the adjustable part 59 between the pivot 94 and the groove 98 for forcing the main portion of said part 59 outwardly about said pivot 94. The reciprocating actuating member 101 is usually wedge-shaped, is revoluble with, and suitably guided in, the main body of the driving means 58, and is pivotally connected at one end to a collar 102 reciprocally movable along the shaft 93. The described means for moving the adjustable part 59 outwardly is, however, only one of many structures which may be used for this purpose.

Motion is transmitted from the driving means 58 to the rack 65 by an intermittently movable power-transmitting member 103, here illustrated as pivoted intermediate of its ends to a bracket 104, and as having one end provided with a roller 105 constantly engaged with the periphery of the driving means 58, and its other end rounded and constantly engaged with one end of the rack 65. The member 103 moves the rack 65 in one direction for actuating the driving member 56 to advance the driven member 55 and the vise connected thereto a single step, and a suitable spring 106 moves said rack in the reverse direction. It thus follows that the spring 106 holds the member 103 in engagement with the periphery of the driving means 58. Providing the adjustable part 59 is set to effect the predetermined movement of the vise, the upper end of the power-transmitting member 103 moves toward the center of the driving means 58 immediately after the adjustable part 59 is first engaged with the roller 105 the inner position of the member 103 being its starting position, and when the cam-shaped peripheral face 96 of the driving means 58 is engaged with said roller 105 the power-transmitting member 103 is reversely moved and effects the desired advance of the vise. Just after an advance step of the vise, the power-transmitting member 103 engages the face 97, and is then in a constant or non-variable initial position, being held in such position by the face 97 which prevents inward movement of the roller 105, and by the spring 106 engaging said roller with the face 97. It is therefore apparent that the

face 97 determines the initial position of the power-transmitting member 103. When, during the sewing of a lot of brooms, the part 59 is adjusted a number of times relatively to the main body of the driving means 58, the power-transmitting member 103, as said driving means rotates, moves inwardly toward the axis of the shaft 93 from its initial position dissimilar distances, as determined by the position of the adjustable part 59, and is moved backwardly to such position by the face 96, thus determining the length of the advance steps of the vise. Consequently, the adjustable part 59 limits the movement of the upper end of the power-transmitting member 103 inwardly toward the axis of the driving means 58 and thereby regulates the outward or return movement of said upper end to its initial position. It is thus apparent that the part 59 and the surface 97 coact, respectively, to allow the upper end of the power-transmitting member 103 to move inwardly toward the shaft 93 to its starting position and to force said upper end outwardly from the shaft 93, and that the position of the part 59 varies the travel of said upper end, and therefore regulates the length of the advance steps of the vise.

By those skilled in the art, it will be understood that by constantly engaging the power-transmitting member 103 with the driving means 58 and the rack 65 in mesh with the driving member 56 connected to the vise, the liability of lost motion and jar of the vise-feeding parts is reduced to a minimum and especially minute changes in the length of the advance steps of the vise may be effected.

My present invention is not limited to a broom-sewing machine, in which the driving means for regulating the length of the advance steps of the vise is provided with an adjustable part movable inwardly from its initial position for determining the length of the steps of the vise, and in order that this may be apparent, I have at Figs. 38 to 42, inclusive, shown a modified construction of driving means, having its adjustable part 58 movable outwardly from an initial position, to give the desired movement to the power-transmitting member 103, and advance the vise by steps of the predetermined length. In this modified construction the adjustable part 59 consists of a disk on the shaft 93, the eccentricity of which to the shaft 93 may be varied by the wedge 101. In varying the eccentricity of the part 59 in this construction, said part moves in a right line relatively to the axis of the shaft 93 against the action of springs 100.

As will be obvious to those skilled in the art, the means, as the collar 102, connected to the adjustable part 59 for varying the position thereof and regulating the advance

steps of the vise, may be adjusted and held in the predetermined position by any suitable means. A particularly desirable construction of said means comprises a lever or power-transmitting member 107, a reciprocating part 108, and an adjustable part or power-transmitting member 109; the lever 107 being pivoted intermediate of its ends, and having one end engaged with a flat surface 110 on the movable vise-jaw 4, Figs. 2 and 3, and its other end provided with a lengthwise slot 111; the reciprocating part 108 being movable lengthwise of a guide 112 in a direction substantially parallel to the shaft 93 and the line of reciprocation of the member 101, and being formed with a depending slotted arm or fork 113 engaged with the collar 102; and the power-transmitting member 109 being adjustable lengthwise of the line of reciprocation of the part 108 and having one end adjustably fixed by a screw 114 to said part 108, and its opposite end formed with a lateral extension 115 arranged substantially parallel to the rear end of the lever 107 and provided with a lengthwise slot 116 alined with the slot 111. Said extension 115 is connected to the rear end of the lever 107 by an adjustable connection comprising a pin 117 having one end of angular cross-section guided in the slot 116 and its other end formed cylindrical and encircled by a sleeve 118 of angular cross-section guided in the slot 111. Any desirable clamp, as a screw 119, holds the pin 117 in its adjusted position relatively to the extension 115. A suitable spring 120 is connected to the frame 1 and the power-transmitting member or lever 107 for holding said lever in engagement with the surface 110 and for also actuating the parts 107, 109, 108, 102, to move the reciprocating member 101 to its position assumed in Fig. 24. The movement of said parts 107, 109, 108, 102 may be limited by any desirable means, as a pair of uprights or standards 121 between which the part 108 is movable. The described connection between the reciprocating collar 102 and the movable vise-jaw 4 is readily assembled and can be adjusted at will. It will be understood, however, that other connections may be used for this purpose, and at Figs. 44 and 45, I have shown a slightly modified construction of this feature of my invention comprising a longitudinally-adjustable link 122 having its opposite ends pivotally connected to the lever engaging the vise and the reciprocating part coacting with the collar.

To those skilled in the art, it will be understood that after the operator has adjusted the connections between the vise-jaw 4 and the collar 102 by moving the part 109 and the connection between the lever 107 and said part 109, the thickness of the

broom, which determines the distance between the jaws 3, 4, causes the movable jaw 4 to vary the position of the end of the lever 107 engaged with said jaw, and to thus control the adjustment of the wedge-shaped member 101 against the action of the spring 120, and through the medium of the parts 107, 109, 108, 102, and thereby regulate the length of the step by step advances of the broom and the length of the stitches. In other words, if a thick broom is interposed between the vise-jaws, the jaw 4 will actuate the parts 107, 109, 108, 102, 101, to move the part 59 against the action of the spring 120 toward its position assumed in Fig. 23 and to properly adjust the position of the part 59 so that the advance steps of the vise will be sufficiently long, whereas if a thin broom is clamped by the jaws 3, 4, said jaw 4 will permit the spring 120 to reversely move these parts 107, 109, 108, 102, 101, and adjust the part 59, so that the steps of the vise will be shortened to produce the desired length of the stitches.

The construction and operation of this broom-sewing machine will now be readily understood upon reference to the foregoing description and the accompanying drawings, and it will be obvious that the construction and arrangement of the component parts thereof may be more or less varied without departing from the spirit of this invention.

Having thus fully described my invention, what I claim as new and desire to secure by Letters Patent, is:—

1. In a broom sewing machine, the combination of opposing jaws for clamping the broom, a broom support for holding the broom independently of said jaws, the broom support comprising clamping parts for engaging the broom, said parts being located within the jaws and one being movable toward and from the other in a direction at a right angle to the direction of the clamping movement of the jaws, substantially as and for the purpose described. 105
2. In a broom-sewing machine, opposing jaws for clamping the broom, and a broom support for holding the broom independently of said jaws, the broom support comprising parts for engaging the broom, said parts being located within the jaws and movable relatively to each other and being pivotally connected to one of the jaws and movable therewith, substantially as and for the purpose set forth. 115
3. In a broom-sewing machine, opposing jaws for clamping the broom, a broom support for holding the broom independently of said jaws, the broom support comprising parts for engaging the broom, said parts being located within the jaws and movable relatively to each other, and being pivotally connected to one of the jaws, such parts 125

being movable on their pivots in a direction at a right angle to the direction of the clamping movement of the opposing jaws, substantially as and for the purpose specified.

5 4. In a broom-sewing machine, opposing jaws for clamping the broom, and a broom-support for holding the broom independently of said jaws, the broom-support comprising a part for engaging the broom and 10 a part for supporting said engaging part, the engaging part being movable relatively to the supporting part by the broom when the broom is being placed in operative relation to said part for adjusting itself to the 15 broom held by said support, substantially as and for the purpose described.

5 5. In a broom-sewing machine, opposing jaws for clamping the broom, and a broom-support for holding the broom independently of said jaws, the broom-support comprising a part for engaging the broom and 20 a part for supporting said engaging part, the engaging part being pivoted to the supporting part and movable on its pivot by 25 the broom when the broom is being placed in operative relation to said part for adjusting itself to the broom held by said support, substantially as and for the purpose set forth.

30 6. In a broom-sewing machine, opposing jaws for clamping the broom, and a broom-support for holding the broom independently of said jaws, the broom-support comprising opposing parts for engaging the broom and parts for supporting said engaging parts, the engaging parts being pivoted, 35 respectively, to the supporting parts and movable on their pivots by the broom when the broom is being placed in operative relation to said part for adjusting themselves 40 to the broom held by said support, substantially as and for the purpose specified.

7. In a broom-sewing machine, opposing jaws for clamping the broom, and a broom-support for holding the broom independently of said jaws, the broom-support comprising a part formed with a projecting arm extending substantially parallel to the axis of the broom held by the support, the free 50 end of said arm yieldingly engaging said broom, substantially as and for the purpose described.

8. In a broom-sewing machine, opposing jaws for clamping the broom, and a broom-support for holding the broom independently of said jaws, the broom-support being formed with upper and lower engaging faces spaced apart and disposed substantially parallel to the axis of the broom, the portion 55 of the engaging part provided with the lower engaging face being resilient and movable laterally against the action of its spring, substantially as and for the purpose set forth.

65 9. In a broom-sewing machine, opposing

jaws for clamping the broom, and a broom-support formed with a curved upper face for engaging the broom, said face being disposed at substantially a right angle to the axis of the broom, said support being 70 also formed with upper and lower broom-engaging faces disposed substantially parallel to such axis when the latter is held by the broom-support, substantially as and for the purpose specified. 75

10. In a broom-sewing machine, opposing jaws for clamping the broom, and a broom-support comprising opposing parts formed with curved upper faces for engaging the broom, each of said parts being also formed 80 with upper and lower broom-engaging faces spaced apart and arranged at an angle to the curved faces of said parts, substantially as and for the purpose described.

11. A broom-sewing machine, opposing jaws for clamping the broom, and a broom-support comprising a part for engaging the broom and a part for supporting the engaging part, the engaging part being pivoted to the supporting part and movable freely 85 on its pivot for adjusting itself to the broom and having a yielding portion engaging the broom, and said supporting part being movable relatively to the opposing jaws, substantially as and for the purpose described. 90

12. In a broom-sewing machine, opposing jaws for clamping the broom, and a broom-support comprising a part movable for clamping the broom independently of the opposing jaws, said broom-support being 100 movable lengthwise of a line substantially coincident with the axis of the broom when said broom is held by the broom-support, substantially as and for the purpose described.

13. In a broom-sewing machine, opposing jaws for clamping the broom, and a broom-support comprising a part carried by one of the opposing jaws and movable relatively thereto for clamping the broom held by said support independently of said jaws, and an 110 engaging part attached to the first-mentioned part and adjustable relatively thereto, substantially as and for the purpose described.

14. In a broom-sewing machine, opposing jaws for clamping the broom, and a broom-support comprising opposing members carried directly by one of said jaws and movable therewith and being movable relatively thereto for clamping the broom independently of said jaws, substantially as and for the purpose set forth. 115

15. In a broom-sewing machine, opposing jaws for clamping the broom, and a broom-support comprising part carried by one of the opposing jaws and adjustable relatively thereto, and an engaging part attached to the first-mentioned part and having a yielding portion movable relatively to the attaching part for clamping the broom independently 120 125 130

ently of the opposing jaws, substantially as and for the purpose described.

16. In a broom-sewing machine, opposing jaws for clamping the broom, and a broom-support comprising a part carried by one of the opposing jaws and movable relatively thereto and an engaging part pivotally connected to the first-mentioned part and movable on its pivot independently of the opposing jaws for engaging the broom, substantially as and for the purpose specified.

17. In a broom-sewing machine, opposing jaws for clamping the broom, and a broom-support comprising a pivoted part having engaging surfaces on opposite sides of its pivot, and means for supporting said pivoted part, substantially as and for the purpose set forth.

18. In a broom-sewing machine, opposing jaws for clamping the broom, and a broom-support comprising part carried by one of the opposing jaws and adjustable relatively thereto in a plurality of directions at an angle to each other, and an engaging part attached to the first-mentioned part for clamping the broom, substantially as and for the purpose described.

19. In a broom-sewing machine, opposing jaws for clamping the broom, and a broom-support mounted on one of the opposing jaws and disconnected from the other jaw, substantially as and for the purpose specified.

20. In a broom-sewing machine, opposing jaws for clamping the broom, and a broom-support mounted on one of the opposing jaws and comprising a part movable for clamping the broom independently of the opposing jaws, substantially as and for the purpose set forth.

21. In a broom-sewing machine, opposing jaws for clamping the broom, a broom-support comprising a part for engaging the broom independently of the opposing jaws, and a lever movable relatively to the opposing jaws for forcing said part toward and from the broom, substantially as and for the purpose described.

22. In a broom-sewing machine, opposing jaws for clamping the broom, a broom-support comprising a part for engaging the broom, movable independently of the opposing jaws a lever for moving said part toward and from the broom, and means for moving the lever, substantially as and for the purpose set forth.

23. In a broom-sewing machine, opposing jaws for clamping the broom, a lever, means for supporting the lever, a broom-support comprising a part for engaging the broom, said part being supported by the lever and adjustable relatively thereto, and means for holding said part in its adjusted position relatively to the lever, substantially as and for the purpose described.

24. In a broom-sewing machine, opposing jaws for clamping the broom, a pair of levers, means for supporting the levers, means for moving the levers relatively to the opposing jaws and the first-mentioned means, and a broom-support comprising opposing parts for engaging the broom, said opposing parts being supported by the levers, substantially as and for the purpose specified.

25. In a broom-sewing machine, opposing jaws for clamping the broom, a pair of levers, means for supporting the levers upon one of the opposing jaws, means for moving the levers relatively to the opposing jaws and the first-mentioned means, and a broom-support comprising opposing parts for engaging the broom, said opposing parts being connected to the levers, substantially as and for the purpose set forth.

26. In a broom-sewing machine, opposing jaws for clamping the broom, a pair of levers, means for pivotally supporting the levers intermediate of their ends, a broom-support comprising opposing parts for engaging the broom, said opposing parts being connected to corresponding ends of the levers, and means coacting with the other ends of the levers for moving the same in reverse directions, substantially as and for the purpose described.

27. In a broom-sewing machine, opposing jaws for clamping the broom, a guide extending in a direction at an angle to that in which the jaws compress the broom, a broom-support comprising a movable part for engaging the broom, a member movable along the guide relatively to said jaws for operating the movable part of the broom-support, and actuating means, substantially as and for the purpose specified.

28. In a broom-sewing machine, opposing jaws for clamping the broom, a plurality of guides, a broom-support comprising a plurality of parts for engaging the broom, a plurality of members movable along the guides for operating the movable parts of the broom-support, and actuating means, substantially as and for the purpose described.

29. In a broom-sewing machine, opposing jaws for clamping the broom, a pair of levers, a broom-support comprising opposing parts for engaging the broom, said parts being adjustable along the levers, and actuating means, substantially as and for the purpose set forth.

30. In a broom-sewing machine, opposing jaws for clamping the broom, a pair of levers, means for pivotally supporting the levers intermediate of their ends upon one of the opposing jaws, a broom-support comprising opposing parts for engaging the broom, said parts being adjustable along corresponding ends of the levers, and means

coacting with the other ends of the levers for moving the same in reverse directions, substantially as and for the purpose specified.

31. In a broom-sewing machine, opposing jaws for clamping the broom, a broom-support comprising opposing parts for engaging the broom, levers having corresponding ends connected to the opposing parts, means for pivotally supporting the levers intermediate of their ends, and a spring coacting with the other ends of the levers, substantially as and for the purpose set forth.
32. In a broom-sewing machine, opposing jaws for clamping the broom, a broom-support comprising a part movable independently of the jaws into and out of engagement with the broom, a cam for moving said part in one direction, and means for moving said part in the opposite direction, when not acted upon by the cam, substantially as and for the purpose described.

33. In a broom-sewing machine, opposing jaws for clamping the broom, a broom-support comprising a part movable independently of said jaws into and out of engagement with the broom, a reciprocating member for moving said part in one direction, a cam for actuating the reciprocating member, and means for moving said part in the opposite direction when not acted upon by said cam, substantially as and for the purpose set forth.

34. In a broom-sewing machine, opposing jaws for clamping the broom, a broom-support comprising opposing parts for engaging the broom, a pair of cams movable simultaneously for forcing said parts in opposite directions and means for moving said parts in the opposite directions when not acted on by said cams, substantially as and for the purpose set forth.

35. In a broom-sewing machine, opposing jaws for clamping the broom, a broom-support comprising opposing parts for engaging the broom, a shaft, a pair of cams mounted on the shaft, said cams being connected to the opposing parts for moving the same and means for moving said parts in the opposite directions when not acted on by said cams, substantially as and for the purpose described.

36. In a broom-sewing machine, opposing jaws for clamping the broom, a broom-support comprising opposing parts for engaging the broom, levers having corresponding ends connected to the opposing parts, means for pivotally supporting the levers intermediate of their ends upon one of the opposing jaws, reciprocating members coacting with the other ends of the levers for moving said levers, a shaft journaled in one of the jaws, a pair of cams mounted on the shaft and coacting with said reciprocating members and means for moving said parts

in the opposite directions when not acted on by said cams, substantially as and for the purpose specified.

37. In a broom-sewing machine, opposing jaws for clamping the broom, a broom-support comprising a part for engaging the broom, means for forcing said part into engagement with the broom independently of the opposing jaws, and means for forcing said part in the reverse direction, substantially as and for the purpose set forth.

38. In a broom-sewing machine, opposing jaws for clamping the broom, a broom-support, a spring for forcing said part into engagement with the broom, and a cam for moving said part in the reverse direction, substantially as and for the purpose described.

39. In a broom-sewing machine, opposing jaws for clamping the broom, a broom-support comprising opposing parts for engaging the broom, yielding means for moving the opposing parts in one direction, and an actuating member movable about an axis for forcing said parts in the reverse direction, substantially as and for the purpose specified.

40. In a broom-sewing machine, opposing jaws for clamping the broom, a broom-support comprising opposing parts for engaging the broom, levers having corresponding ends connected to the opposing parts, means for pivotally supporting the levers intermediate of their ends upon one of the opposing jaws, a spring coacting with the other ends of the levers, an actuating member journaled in one of the jaws, and cams mounted on said actuating member and moving the levers against the action of the spring, substantially as and for the purpose set forth.

41. In a broom-sewing machine, opposing jaws for clamping the broom, one jaw being movable toward and from the other, a broom-support comprising a part movable independently of the opposing jaws for engaging the broom, and an actuating member connected to the movable jaw and to said part of the broom-support, substantially as and for the purpose described.

42. In a broom-sewing machine, opposing jaws for clamping the broom, one jaw being movable toward and from the other, a broom-support comprising a part for engaging the broom, an actuating member movable about an axis, a cam on the actuating member for operating the movable jaw, and a cam on said member for moving said part of the broom-support, substantially as and for the purpose specified.

43. In a broom-sewing machine, opposing jaws for clamping the broom, one jaw being movable toward and from the other, a broom-support comprising opposing parts for engaging the broom, yielding means for

- moving the opposing parts relatively to each other, an actuating member movable about an axis, means between the actuating member and the movable jaw for operating 5 said jaw, and means between the actuating member and the opposing parts for moving said parts against the action of the yielding means, substantially as and for the purpose set forth.
- 10 44. In a broom-sewing machine, opposing jaws for clamping the broom, one jaw being movable toward and from the other, a broom-support comprising opposing parts for engaging the broom, levers having corresponding ends connected to the opposing parts, means for pivotally supporting the levers intermediate of their ends on one of the opposing jaws, yielding means coacting with the other ends of the levers for moving 15 said levers, an actuating member having a pivotal shaft journaled in one of the jaws, a cam on the actuating member for operating the movable jaw, and cams on the ends of the pivotal shaft of the actuating 20 member for moving the opposing parts of the broom-support against the action of the yielding means substantially as and for the purpose described.
45. In a broom-sewing machine, opposing 30 jaws for clamping the broom, one jaw being movable toward and from the other, a broom-support comprising a part movable independently of the opposing jaws for engaging the broom, said broom-support being movable as a whole relatively to the opposing jaws, and an actuating member connected to the movable jaw for operating said jaw, and connected to the broom-support for moving said part of the broom- 35 support independently of the opposing jaws and for moving the broom-support as a whole relatively to the opposing jaws, substantially as and for the purpose specified.
46. In a broom-sewing machine, opposing 40 jaws for clamping the broom, one jaw being movable toward and from the other, a broom-support comprising a part movable for engaging the broom, said broom-support being movable relatively to the opposing 45 jaws lengthwise of a line substantially coincident with the axis of the broom when said broom is clamped by the opposing jaws, and an actuating member movable about an axis, a cam on the actuating member for 50 operating the movable jaw, a cam on the actuating member for moving said part of the broom-support, and means for moving said broom-support lengthwise of a line substantially coincident with said axis of the broom, substantially as and for the purpose set forth.
47. In a broom-sewing machine, opposing 55 jaws for clamping the broom, one jaw being movable toward and from the other, a broom-support comprising opposing parts for engaging the broom, yielding means for moving the opposing parts relatively to said jaws, an actuating member, means between the actuating member and the movable jaw for operating said jaw, means between the actuating member and the opposing parts for moving said parts against the action of the yielding means, and means operated by the actuating member for moving the broom-support lengthwise of a line substantially coincident with the axis of the broom when said broom is clamped by the opposing jaws, substantially as and for the purpose described.
48. In a broom-sewing machine, opposing 60 jaws for clamping the broom, one jaw being movable toward and from the other, a broom-support comprising opposing parts for engaging the broom, levers having corresponding ends connected to the opposing parts, means for pivotally supporting the levers intermediate of their ends on one of the opposing jaws, yielding means coacting with the other ends of the levers, an actuating member journaled in one of the jaws, means between the actuating member and the movable jaw for operating said jaw, means between the actuating member and said other ends of the levers for moving the opposing parts against the action of the yielding means, and means operated by the actuating member for moving the broom-support lengthwise of a line substantially coincident with the axis of the broom when said broom is clamped by the opposing jaws, substantially as and for the purpose specified.
49. In a broom-sewing machine, a vise movable to and fro, and mechanism for feeding the vise comprising two members, one a screw revoluble in reverse directions about an axis, substantially parallel to a line coincident with the axis of the broom held by the vise, and the other a driving member for the screw, and means between the screw and the driving member for rotating the screw in one direction with the driving member and for permitting one of said members to rotate in the reverse direction relatively to the other member, and connections between the vise and the screw for transmitting movement of the vise to the screw during the retrograde movement of the vise, and thereby moving the screw in the reverse direction, substantially as and for the purpose specified.
50. In a broom-sewing machine, a vise movable to and fro, and mechanism for feeding the vise comprising two parts, one a screw connected to the vise and revoluble in reverse directions, and the other a pinion for driving the screw, means between the screw and the pinion for rotating the screw in one direction with the pinion, and for permitting one of said two parts to rotate in

the reverse direction relatively to the other part, a reciprocating part meshing with the pinion for rotating the same, means for moving the reciprocating part in one direction, and a spring for moving said part in an opposite direction, substantially as described.

51. In a broom-sewing machine, a vise movable to and fro, and mechanism for feeding the vise comprising two members, one a screw connected to the vise and revoluble in reverse directions, and the other a driving member for the screw, means between the screw and the driving member for rotating the screw in one direction with the driving member, and means for forcing the first-mentioned means from operative position for permitting each of said two members to rotate in the reverse direction relatively to the other member, substantially as and for the purpose described.

52. In a broom-sewing machine, a vise movable to and fro, and mechanism for feeding the vise comprising a screw connected to the vise and revoluble in reverse directions, a driving member for the screw concentric therewith, means between the screw and the driving member for rotating the screw in one direction with the driving member, and means for forcing the first-mentioned means from operative position for permitting said screw to rotate in the reverse direction relatively to the driving member, substantially as and for the purpose set forth.

53. In a broom-sewing machine, a vise movable to and fro, and mechanism for feeding the vise comprising a shaft, two members, one a screw connected to the vise and fixed to the shaft, and the other a driving member supported by the shaft and loose thereon, means between the screw and the driving member for rotating the screw in one direction with the driving member, and means for forcing the first-mentioned means from operative position for permitting one of said two members to rotate in the reverse direction relatively to the other member, substantially as and for the purpose specified.

54. In a broom-sewing machine, a vise movable to and fro, and mechanism for feeding the vise comprising a shaft revoluble in reverse directions as the vise moves to and fro, two members, one a revoluble driven member connected to the vise and fixed to the shaft, and the other a revoluble driving member, and means between the driven and driving members for rotating one member with the other in one direction, and for permitting one member to rotate in the reverse direction relatively to the other member, substantially as and for the purpose described.

55. In a broom-sewing machine, a vise

movable to and fro, and mechanism for feeding the vise comprising a rack connected to the vise, a shaft revoluble in reverse directions about an axis at an angle to the direction of movement of the vise as the vise moves to and fro, a screw coacting with the rack and fixed to the shaft, a driving member for the screw, means between the screw and the driving member for rotating the screw in one direction with the driving member, and means for forcing the first-mentioned means from operative position for permitting said screw to rotate in the reverse direction relatively to the driving member, substantially as and for the purpose set forth.

56. In a broom-sewing machine, a vise movable to and fro, and mechanism for feeding the vise comprising a rack connected to the vise, a shaft revoluble in reverse directions as the vise moves to and fro, a screw coacting with the rack and fixed to the shaft, a driving member for the screw supported by the shaft and loose thereon, and means between the screw and the driving member for rotating the screw in one direction with the driving member, and for permitting said screw to rotate in the reverse direction relatively to the driving member, substantially as and for the purpose specified.

57. In a broom-sewing machine, a vise movable to and fro, and mechanism for feeding the vise comprising a driven member connected to the vise and movable in reverse directions, a driving member movable in reverse directions, a ratchet-device between the driven and driving members for moving the driven member in one direction with the driving member, and for permitting one of said members to move in the reverse direction relatively to the other member, and means for preventing the transmission of motion by the ratchet-device and permitting said other member to move in the reverse direction relatively to the member movable therewith in one direction, substantially as and for the purpose described.

58. In a broom-sewing machine, a vise movable to and fro, and mechanism for feeding the vise comprising two members, one a screw connected to the vise and revoluble in reverse directions as said vise moves to and fro, and the other a driving member for the screw revoluble in reverse directions, a ratchet-device between the screw and the driving member for rotating the screw in one direction with the driving member, and for permitting one of said members to rotate in the reverse direction relatively to the other member, and means for preventing the transmission of motion by the ratchet-device and permitting said other member to rotate in the reverse direction relatively to the member revoluble

therewith in one direction, substantially as and for the purpose set forth.

59. In a broom-sewing machine, a vise movable to and fro, and mechanism for feeding the vise comprising a reversely-rotating screw connected to the vise, a reversely rotating driving member, a ratchet-device between the screw and the driving member for rotating the screw in one direction with the 10 driving member, and for permitting the driving member to rotate in the reverse direction relatively to the screw, and means for preventing the transmission of motion by the ratchet-device and permitting the 15 screw to rotate in the reverse direction relatively to the driving member, substantially as and for the purpose specified.

60. In a broom-sewing machine, a vise movable to and fro, and mechanism for feeding the vise comprising a shaft revolvable in reverse directions as the vise moves to and fro, two members, one a driven member connected to the vise and fixed to the shaft, and the other a driving member supported 25 by the shaft and loose thereon, said driving member being revolvable in reverse directions, a ratchet-device between the driven and driving members for rotating the driven member in one direction with the driving 30 member, and for permitting the driving member to rotate in the reverse direction relatively to the driven member, and means for preventing the transmission of motion by the ratchet-device and permitting the 35 driven member to rotate in the reverse direction relatively to the driving member, substantially as and for the purpose described.

61. In a broom-sewing machine, a vise movable to and fro, and mechanism for feeding the vise comprising a screw connected to the vise and revolvable in reverse directions as the vise moves to and fro, a driving member for the screw, means between the screw and the driving member 45 for rotating the screw in one direction with the driving member, and means for preventing the transmission of motion by the first-mentioned means to the screw and permitting said screw to rotate in the reverse 50 direction, substantially as and for the purpose set forth.

62. In a broom-sewing machine, a vise movable to and fro, and mechanism for feeding the vise comprising a driven member connected to the vise and movable in reverse directions as the vise moves to and fro, a driving member, a ratchet-device between said members for moving the driven member in one direction with the driving 55 member, said device including ratchet-teeth connected to one of said members, and a pawl connected to the other member, means for actuating the driven member in the reverse direction and means for forcing the 60 pawl from operative position and thereby 65

permitting the driven member to rotate in the reverse direction relatively to the driving member, substantially as and for the purpose specified.

63. In a broom-sewing machine, a vise 70 movable to and fro, and mechanism for feeding the vise comprising a shaft revolvable in reverse directions as the vise moves to and fro, two members, one a driven member connected to the vise and fixed to the 75 shaft, and the other a driving member supported by the shaft and loose thereon, said driving member being revolvable in reverse directions, a ratchet-device between said members for moving the driven member in 80 one direction with the driving member, said device including a ratchet-wheel connected to one of said members, and pawls connected to the other member, means for actuating the driven member in the reverse direction, 85 and means for forcing the pawls from operative position and thereby permitting the driven member to rotate in the reverse direction relatively to the driving member, substantially as and for the purpose de- 90 scribed.

64. In a broom-sewing machine, a vise movable to and fro, and mechanism for feeding the vise comprising a driven member connected to the vise and revolvable in 95 reverse directions, a driving member, means between said members for rotating the driven member in one direction, and means movable lengthwise of the axis of the driven member for preventing the transmission of 100 motion by the first-mentioned means to the driven member and permitting said driven member to rotate in the reverse direction, substantially as and for the purpose set forth.

65. In a broom-sewing machine, a vise movable to and fro, and mechanism for feeding the vise comprising a driven member connected to the vise and revolvable in reverse directions, a driving member, a 110 ratchet-device including a ratchet-wheel connected to one of said members, and a pawl journaled in the other member and coacting with the ratchet-wheel, and means coacting with said pawl for forcing the 115 same out of operative engagement with the ratchet-wheel, substantially as and for the purpose specified.

66. In a broom-sewing machine, a vise movable to and fro, and mechanism for 120 feeding the vise comprising a shaft revolvable in reverse directions, a driven member connected to the vise and fixed to the shaft, a driving member supported by the shaft and loose thereon, said driving member being revolvable in reverse directions, a ratchet-device including a ratchet-wheel connected to one of said members, and a pawl journaled in the other member and coacting with the ratchet-wheel, and a sleeve 125 130

supported by the shaft and movable relatively thereto for forcing the pawl from operative engagement with the ratchet-wheel, substantially as and for the purpose described.

67. In a broom-sewing machine, a vise movable to and fro, mechanism for feeding the vise comprising a driven member connected to the vise and movable in reverse directions as the vise moves to and fro, a driving member, means between said members for moving the driven member in one direction, and means for preventing the transmission of motion by the first-mentioned means to the driven member and permitting said driven member to move in the reverse direction, and means movable with the vise for actuating said means preventing the transmission of motion to the driven member, substantially as and for the purpose set forth.

68. In a broom-sewing machine, a vise movable to and fro, mechanism for feeding the vise comprising two members, one a screw connected to the vise and revoluble in reverse directions as the vise moves to and fro, and the other a driving member for the screw revoluble in reverse directions, a ratchet-device between said members for rotating the screw in one direction with the driving member, and for permitting the driving member to rotate in the reverse direction relatively to the screw, and means for forcing a part of the ratchet-device from operative position and thereby permitting said screw to rotate in the reverse direction relatively to the driving member, and means carried by the vise for actuating the means forcing said part of the ratchet-device from operative position, substantially as and for the purpose specified.

69. In a broom-sewing machine, a vise movable to and fro, mechanism for feeding the vise comprising a shaft revoluble in reverse directions, a driven member connected to the vise and fixed to the shaft, a driving member supported by the shaft and loose thereon, a ratchet-device including a ratchet-wheel connected to one of said members, and a pawl connected to the other member and coacting with the ratchet-wheel, and means supported by the shaft and movable relatively thereto for forcing one of said parts of the ratchet-device from operative position, and a treadle for actuating said last-mentioned means, substantially as and for the purpose described.

70. In a broom-sewing machine, a vise movable to and fro, and mechanism for feeding the vise comprising a driven member connected to the vise and having a socket extending inwardly from one face thereof, a driving member having a part thereof movable in the socket and a part projecting beyond said socket, a ring sur-

rounding the driving member and forming a cover for the portion of the socket encircling the driving member, and means within the socket carried by the driven member for engaging the part of the driving member within said socket, substantially as and for the purpose set forth.

71. In a broom-sewing machine, a vise movable to and fro, and mechanism for feeding the vise comprising a screw revoluble in reverse directions as the vise moves to and fro and having a socket extending inwardly from one face thereof, a driving member provided with an annular groove, a series of ratchet-teeth at one side of the groove movable in the socket, and a series of teeth at the other side of the groove movable outside of the socket, a ring surrounding the driving member and having its inner portion arranged in the annular groove of the driving member, said ring forming a cover for the portion of the socket encircling the driving member, pawls journaled in the screw and having means within the socket for coacting with the series of ratchet-teeth, and means for coacting with the other series of teeth of the driving member, substantially as and for the purpose specified.

72. In a broom-sewing machine, a vise movable to and fro, and mechanism for feeding the vise comprising a screw connected to the vise and revoluble in reverse directions as said vise moves to and fro, and an antifriction bearing for resisting the tendency of the screw to move endwise in one direction, substantially as and for the purpose described.

73. In a broom-sewing machine, a vise movable to and fro, and mechanism for feeding the vise comprising a screw connected to the vise and revoluble in reverse directions as said vise moves to and fro, movable power-transmitting means carried by the screw, and means coacting with said power-transmitting means for rotating the screw, means for forcing said power-transmitting means from its operative position, and an antifriction bearing for reducing the friction incidental to the operation of the last-mentioned means, substantially as and for the purpose set forth.

74. In a broom-sewing machine, a vise movable to and fro, mechanism for feeding the vise comprising a screw connected to the vise and revoluble in reverse directions as said vise moves to and fro, and friction-means for holding the screw against abnormal movement, substantially as and for the purpose specified.

75. In a broom-sewing machine, a vise movable to and fro, mechanism for feeding the vise comprising a shaft revoluble in reverse directions as the vise moves to and fro, a driven member connected to the vise and fixed to the shaft, and a driving member

5 supported by the shaft and loose thereon, a friction-collar fixed to the shaft, and a friction-collar loose on the shaft and movable lengthwise of the shaft toward and from the former collar, said collars being normally engaged with each other for holding the vise against abnormal movements, substantially as and for the purpose described.

10 76. In a broom-sewing machine, a vise movable to and fro, mechanism for feeding the vise comprising a driven member connected to the vise and revoluble in reverse directions as said vise moves to and fro, friction-means for holding the driven member 15 against abnormal movements, and means movable with the vise for releasing the driven member from the friction-means, substantially as and for the purpose set forth.

20 77. In a broom-sewing machine, a vise movable to and fro, mechanism for feeding the vise comprising a shaft revoluble in reverse directions as the vise moves to and fro, a driven member connected to the vise 25 and fixed to the shaft, and a driving member supported by the shaft and loose thereon, a friction-collar fixed to the shaft, a friction-collar loose on the shaft and held from turning therewith, said loose collar being movable relatively to the first-mentioned collar and normally engaged therewith, means for moving the loose collar toward the other collar, and a treadle for moving said loose collar in the reverse direction, substantially 30 as and for the purpose specified.

35 78. In a broom-sewing machine, a vise movable to and fro, mechanism for feeding the vise comprising two members, one a screw connected to the vise and movable in 40 reverse directions as said vise moves to and fro, and the other a driving member, and means between the screw and the driving member for moving the screw in one direction with the driving member and for permitting one of said members to move in the 45 reverse direction relatively to the other member, friction-means for holding the screw against abnormal movements, and means for preventing the transmission of motion by said means between the screw and the driving member, and for releasing the screw from the friction-means, substantially 50 as and for the purpose described.

55 79. In a broom-sewing machine, a vise movable to and fro, and mechanism for feeding the vise comprising a screw connected to the vise and revoluble in reverse directions as said vise moves to and fro, a rack associated with the vise and meshing 60 with the screw, a driving member for rotating the screw in one direction, and a member for rotating the screw in the reverse direction, substantially as and for the purpose specified.

65 80. In a broom-sewing machine, a vise

movable to and fro, and mechanism for feeding the vise comprising two members, one a screw connected to the vise and revoluble in reverse directions as said vise moves to and fro, and the other a driving member 70 for the screw revoluble in reverse directions, a rack associated with the vise and meshing with the screw power-transmitting means between the screw and the driving member for rotating the screw in one direction with the driving member, and for permitting one of said two members to rotate in the reverse direction relatively to the other member, means for preventing the transmission of motion by the power-transmitting means and permitting said other member to move in the reverse direction relatively to the member revoluble therewith in one direction, and a member for rotating the screw in the reverse direction, 75 substantially as and for the purpose described.

80 81. In a broom-sewing machine, a vise movable to and fro, and mechanism for feeding the vise comprising a shaft revoluble in 90 reverse directions as the vise moves to and fro, a driven member connected to the vise and fixed to the shaft, said driven member being connected to the vise to transmit motion thereto in one direction and being 95 locked against receiving motion from the vise, a driving member for rotating the shaft in one direction, and a member for rotating the shaft in the reverse direction, substantially as and for the purpose set forth.

100 82. In a broom-sewing machine, a vise movable to and fro, and mechanism for feeding the vise comprising a driven member connected to the vise and movable in reverse directions, power-driven means for moving 105 the driven member in one direction, said means being locked against receiving motion from the vise and a hand-piece connected to the driven member for moving the same in the reverse direction, substantially as and 110 for the purpose specified.

115 83. In a broom-sewing machine, a vise movable to and fro, and mechanism for feeding the vise comprising a driven member connected to the vise and movable in reverse directions, said driven member transmitting motion to the vise in one direction and being locked against receiving motion from the vise when the vise is moved in the reverse direction, means for moving the driven member in one direction, and a reciprocating member for moving the driven member in the reverse direction, substantially as and for the purpose described.

120 84. In a broom-sewing machine, a vise 125 movable to and fro, and mechanism for feeding the vise comprising a driven member connected to the vise and movable in reverse directions, means for moving the driven member in one direction, and means 130

movable with the vise and movable relatively thereto for moving the driven member in the reverse direction, substantially as and for the purpose set forth.

5 85. In a broom-sewing machine, a vise movable to and fro, and mechanism for feeding the vise comprising a driven member connected to the vise and movable in reverse directions, means for moving the 10 driven member in one direction, a reciprocating rack connected to the driven member for moving said driven member in the reverse direction, and a hand-lever pivoted to the vise and connected to the reciprocating 15 rack, substantially as and for the purpose specified.

86. In a broom-sewing machine, a vise movable on an axis to and fro, and mechanism for feeding the vise comprising a 20 screw connected to the vise and revoluble in reverse directions as said vise moves to and fro, a driving member for rotating the screw in one direction, and a lever pivoted to the vise above the axis of said vise and 25 connected to the screw for rotating said screw in the reverse direction, substantially as and for the purpose described.

87. In a broom-sewing machine, a vise 30 movable step by step, and mechanism for feeding the vise comprising a power-transmitting member movable intermittently for advancing the vise step by step, driving means having a part for determining the starting position of said member, means controlled by the vise for adjusting said part of the driving means and thereby varying the starting position of said member, and means for returning said member to its starting position, substantially as and for 35 the purpose specified.

88. In a broom-sewing machine, a vise 40 movable step by step, and mechanism for feeding the vise comprising a power-transmitting member movable intermittently for advancing the vise step by step, means for determining the starting position of said member, means controlled by the thickness of the broom for adjusting the first-mentioned means to vary the starting position 45 of the power-transmitting member, means for moving the power-transmitting member 50 from its starting position to the same advance position upon each advance step of the vise, and means for returning the power-transmitting member to its starting position, 55 substantially as and for the purpose set forth.

89. In a broom-sewing machine, a vise 60 movable step by step, and mechanism for feeding the vise comprising a rotary driving means having a movable part for regulating the amount of movement of the vise, and means controlled by the relative position of the jaws of the vise for adjusting

said movable part, substantially as and for 65 the purpose set forth.

90. In a broom-sewing machine, a vise 70 movable in one direction step by step during the sewing of the broom, and movable in the opposite direction, and mechanism for feeding the vise comprising a driven member connected to the vise and movable in reverse directions as said vise moves to and fro, a reciprocating part for moving the 75 driven member in one direction, means for returning the reciprocating part, a power-transmitting member for moving the reciprocating part against the action of said means, the power-transmitting member being forced to its starting position by the reciprocating part, and a driving means having 80 means for determining the starting position of the power-transmitting member, and adjustable means for varying the starting position of the power-transmitting member 85 and thereby regulating the length of the steps of the vise, substantially as and for the purpose set forth.

91. In a broom-sewing machine, a vise 90 movable step by step, and mechanism for feeding the vise comprising a rotary driving member provided with an engaging face substantially equidistant throughout its length from the axis of the member, a cam-shaped face, and a cam-shaped part pivoted 95 intermediate of its ends to the main body of the driving member on an axis arranged substantially parallel to the first-mentioned axis, said cam-shaped part being adjustable for controlling the amount of movement of the vise, and means between said driving member and the vise, substantially as and for the purpose specified.

92. In a broom-sewing machine, a vise 100 movable step by step and provided with a movable jaw, and mechanism for feeding the vise comprising a driving means 105 provided with a part adjustable for regulating the amount of movement of the vise, a pivoted lever having one end engaged with the movable jaw of the vise and its other end connected to the adjustable part of the driving means for controlling the movement of the vise, substantially as and for the purpose specified.

93. In a broom-sewing machine, a vise 110 movable step by step, and mechanism for feeding the vise comprising a driving means provided with a part adjustable for regulating the amount of movement of the vise, 115 means between the vise and the adjustable part for operating said part including a power-transmitting member connected to the adjustable part of the driving means for varying the position thereof and thereby regulating the amount of movement of the vise, a second power-transmitting member, and an adjustable connection between said 120 125

power-transmitting members, substantially as and for the purpose described.

94. In a broom - sewing machine, a vise movable step by step, and mechanism for feeding the vise comprising a power-transmitting member for advancing the vise step by step, a rotary driving means provided with a movable part adjustable for varying starting position of the power-transmitting member and thereby regulating the length of the steps of the vise, and with a reciprocally - movable wedge - shaped member for moving said adjustable part toward and from the axis of the driving means, and a 10 spring for holding said part in engagement with the wedge - shaped member, substantially as and for the purpose described.

95. In a broom-sewing machine, a vise movable step by step, and mechanism for feeding the vise comprising a power-transmitting member for advancing the vise step by step, a rotary driving means provided with a part adjustable for varying the starting position of the power-transmitting member and thereby regulating the steps of the vise, movable means coacting with the adjustable part of the driving means for varying the position of said adjustable part, said movable means being governed in its 25 operation by the thickness of the broom in the vise, substantially as and for the purpose set forth.

96. In a broom - sewing machine, a vise movable step by step, and mechanism for feeding the vise comprising a driving means provided with a movable part adjustable for regulating the amount of movement of the steps of the vise, means between the vise and the movable part of the driving means for 30 adjusting said part including means connected to the adjustable part of the driving means for varying the position thereof and thereby regulating the amount of movement of the steps of the vise, said means being 35 provided with a lateral extension having a lengthwise slot, a second means having a portion thereof arranged substantially parallel to the lateral extension and provided with a lengthwise slot alined with the 40 former slot, and an adjustable connection between said means comprising a pin having an end of angular cross-section guided in one of the slots, the other end of the pin 45

being cylindrical, a sleeve of angular cross-section mounted on said other end of the pin 55 and guided in the slot, and a clamping member for securing said pin to one of said means, substantially as and for the purpose specified.

97. In a broom - sewing machine, a vise 60 movable step by step, and mechanism for feeding the vise comprising a driving means provided with a part adjustable for regulating the amount of movement of the steps of the vise, means between the vise and the 65 movable part of the driving means for adjusting said part including a reciprocating part connected to the movable part of the driving means for varying the position of the adjustable part and thereby regulating 70 the amount of movement of the steps of the vise, and means for actuating the reciprocating part, said means being adjustable relatively to the reciprocating part substantially parallel to the line of its reciprocal movement, substantially as and for the purpose described.

98. In a broom - sewing machine, a vise movable step by step, and mechanism for feeding the vise comprising a rotary driving 80 means provided with a part adjustable for regulating the amount of movement of the steps of the vise, a part revoluble with the driving means and adjustable relatively thereto for varying the position of the adjustable part of the driving means and thereby regulating the amount of movement of the steps of the vise, means between the vise and the second-mentioned part including a reciprocating part for moving said 90 second-mentioned part relatively to the driving means, and means for actuating the reciprocating part, said means being adjustable relatively to the reciprocating part substantially parallel to the line of its reciprocal movement, substantially as and for the purpose set forth.

In testimony whereof, I have hereunto signed my name in the presence of two attesting witnesses, at Syracuse, in the county 100 of Onondaga, in the State of New York, this 1st day of Oct., 1904.

WILLARD C. LIPE.
